UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

BOLSTER-GUIDE.

1,170,595.

Specification of Letters Patent.

Patented Feb. 8, 1916.

Application filed June 18, 1915. Serial No. 34,844.

To all whom it may concern:

Be it known that I, WALTER S. ADAMS, a citizen of the United States, and a resident of the city and county of Philadelphia and State of Pennsylvania, have invented certain new and useful Improvements in Bolster-Guides, of which the following is a specification.

The object of this invention is to provide a device of this class which will eliminate the necessity of using chafing plates between a car truck bolster and truck transoms, keep the bolster a fixed distance from the transoms but yet allow the usual movements transversely of the truck and otherwise as may be required by the conditions of service. These and other objects are accomplished by my invention, a more particular description of which will appear below.

Reference is to be had to the accompanying drawings in which—

Figure 1 is a plan view of a portion of a car truck to which my improved bolster guide is applied, portions of the truck being shown in dotted lines; Fig. 2 is a front elevation of the same; Fig. 3 is a plan view of a different form of truck to which my invention has been applied; Fig. 4 is a front elevation of the same; Fig. 5 is a sectional view on the line 5—5 of Fig. 3 looking in the direction of the arrows; Fig. 6 is a side elevation of one of the pins upon which the guide link is mounted; Fig. 7 is a perspective view of a bracket; Fig. 8 is a sectional view of the end of the guide link and bearing with bearing cap; and Fig. 9 is a plan view of a bearing cap.

Throughout the several views of the drawings, similar reference characters designate similar parts.

The car truck to which my invention may be applied may be of conventional or desired construction and is provided with side frames 1 and transoms 2, said transoms being suitably united by a tie bar 3. Gusset plates 4 also secure the transoms to the side frame 1, said gusset plates being secured thereto by bolts 5.

A bolster 6 is mounted between the transoms upon suitable springs. In Figs. 1, 2 and 3 it is mounted upon leaf springs 7 between the ends of which are mounted coil springs 8 with caps 9. In Figs. 3, 4 and 5, the bolster is mounted upon leaf springs 10, on top of which are mounted coil springs 11,

the bolster being supported on said coil springs. To hold the bolster free and keep it out of contact with the transoms mechanism may be used which will now be described.

Referring to the construction shown in Figs. 1 and 2. Secured to the bolster 6 by means of bolts 12 or other equivalent means, is a U-shaped bar 13. Extending through a conical perforation in said U-shaped bar 13 is a pin 14, having a practically spherical head 15, a tapered portion below said head and a screw threaded end 17 upon which are mounted a nut 18 and lock washer 19 securing the pin in place. The tapered portion 16 of the pin 14 fits into the conical perforation in the U-bar 13 above mentioned. Secured to one of the transoms by bolts 20 is a bracket 21 having a flat portion 22, by which it is secured to the transom, and an upright portion 23. The upright portion 23 has a conical perforation 24 and angled corners 25. Mounted in the conical perforation is a pin 14, identical with the pin 14 before mentioned and having the spherical head 15, tapered portion 16, threaded end 17, nut 18 and washer 19. Extending between the two pins 14 is a link 26, said link being made up of two parts 27 between which are a number of plates 28. The plates 28 and parts 27 are held together as one unit by bolts 29. The link 26 thus made has two perforations shaped to fit the spherical heads 15 of the pins 14. From the foregoing it will be seen that the link 26 extending between the pins 14 and mounted upon the spherical heads 15 prevents the bolster from coming into contact with the transoms while at the same time, the spherical heads act as universal joints for the link 26 and allow the bolster a free up and down movement and movement transversely of the truck. The corners 25 on the bracket 21 are angled to prevent the link from contacting therewith during movement of the bolster. The wear at the joints may be regulated by removing some of the plates 28 from the link 26.

In Figs. 1 to 6 it will be noted that the spherical heads 15 on the pins 14 are not entirely spherical, their outer ends being flattened. In Fig. 8 I have shown the pins 14 provided with complete spherical heads 31. Secured to the link 26 are caps 32 which fit over the tops of these heads 31, these caps

comprising a central dome 33, having an opening 33^a for lubrication, which fits the end of the head 31 and ears 34 having perforations 34^a through which extend rivets 5 or bolts 35 securing the cap to the link 26. The rivets or bolts 35 do not extend through the entire link but only through one of the outer portions 27 as shown in Fig. 8.

In the structure shown in Figs. 3, 4 and 10 5, a bracket 30 extends upward from the bolster and in which is mounted the pin 14. Another pin 14 is secured to one of the transoms and the link 26 above described extends between these pins 14, the link in this 15 instance being with its widest side uppermost as shown.

From the foregoing, the operation of my improved device will be readily understood. The link prevents the bolster from contacting 20 with the transoms, thus obviating the necessity for the chafing plates usually used thereon, but readily allows an up and down movement of the bolster or a movement of the same transversely of the car truck.

25 The bolster guide is, of course, duplicated at both ends of the bolster, or at appropriate points along the length of the bolster; and instead of having the bolster guides extending in the same direction, they may extend 30 in directions opposite to each other.

From the foregoing description of my invention, it is obvious that the same is not restricted to the precise embodiment shown herein, but is broad enough to cover all 35 structures coming within the scope of the annexed claims.

Having described my invention, what I claim is:

1. In a car truck, a frame, a bolster movable in said frame, a bearing comprising a spherical projection on said bolster, a bearing comprising a spherical projection on said frame, and a link variable in thickness with relation to said bearings extending between 40 said bearings and mounted thereon.

2. In a car truck, a frame, a bolster 45 movable within said frame, a bearing on said bolster comprising a pin having a spherical head, a like bearing mounted on the truck frame and a link variable in thickness with relation to said bearings extend-

ing between said bearings and movably mounted thereon.

3. In a car truck, a frame, a bolster movably mounted within said frame, a bearing 55 on the bolster comprising a pin secured thereto having a spherical head, a like bearing secured to the truck frame, and a link variable in thickness with relation to said bearings extending between said bearings 60 and having perforations fitting over said spherical heads and allowing a movement of the link thereon.

4. In a car truck, a truck frame, a bolster movably mounted within said frame, a 65 bracket on the bolster, a pin having a spherical head mounted on said bracket, a bracket on the truck frame, a pin having a spherical head mounted on said bracket and a link comprising two outer parts with a 70 series of plates between them having perforations adapted to fit over said spherical heads extending between said pins.

5. In a car truck, a truck frame, a bolster movably mounted within said frame, a 75 bracket secured on the bolster, a pin secured in said bracket having a spherical head; a bracket secured to the truck frame, a pin secured in said bracket having a spherical head and a link comprising two 80 outer parts and a series of plates between said outer parts, said link extending between the spherical heads and having perforations fitting over said heads and allowing movement of said link.

6. In a car truck, a truck frame, a bolster movably mounted within said frame, a bearing comprising a spherical projection on said bolster, a bearing comprising a spherical projection on said frame, a link variable 90 in thickness with relation to said bearings extending between the same and having perforations fitting over said spherical heads and allowing a movement of the link thereon and caps secured to said link and fitting 95 over the portions of the bearings extending outside of the perforations in the link.

Signed at the city and county of Philadelphia, and State of Pennsylvania, this 2nd day of June, 1915.

WALTER S. ADAMS.
